APPARATUS FOR USE IN THE REPAIR OF SHOES

Frederick A. Prahl, Jr., Danvers, Mass., assignor to United Shoe Machinery Corporation, Borough of Flemington, N. J., a corporation of New Jersey

Application December 31, 1938, Serial No. 248,801

15 Claims. (Cl. 12—1)

This invention relates to apparatus for use in the repair of shoes and more particularly to that class of apparatus commonly known as repair outfits. As heretofore constituted, such outfits consist of an open framework of iron carrying bearings for a shaft or shafting on which are mounted various rotary tools for abrading, buffing, polishing, grinding, trimming, etc. the soles, heels and bottom edges of repaired shoes. Such outfits also commonly include draft hoods partially shrouding such of the individual tools as remove chips or scourings from the work, and a dust collector having a fan for withdrawing the fine dust or chips through the hoods as they are removed by the tools. The tool shafting is commonly driven by an electric motor, the power being transmitted through belting running over pulleys fixed to the motor shaft and to the tool shaft. In some instances, repair outfits of this character also include a stitching machine appropriate for repair work mounted on a portion of the frame.

Constituted as above described, repair equipment serves very well its purely mechanical purposes, but its installation and use are attended by serious objections, inconveniences and even hazards which it is the broad object of this invention to overcome. For example, the appearance of an aggregation of tools supported in an open iron framework is unsightly and inappropriate against a background of modern interior decoration as found in many up-to-date shoe repair shops, and this unsightliness is often aggravated by dust and dirt which, because such structures are difficult to clean, accumulate on the open framework. The tools are dangerously exposed and the lubricated bearings for the shafting and motor exude grease which is frequently transferred to the clothing of the operators and drips to portions of the frame or to the floor. The belting transmitting power from the motor equipment to the shafting is exposed except as it may sometimes be shrouded by an ordinary belt cover.

With these considerations in mind, it is the object of the present invention to provide apparatus for shoe repair work in which the power plant, dust collecting system and substantially all elements of the apparatus other than the tools and shafting are encased on all sides in a cabinet-like structure or casing, the shafting with the tools mounted thereon being arranged over a bench-high deck and protected by an open-front hood which extends forwardly over the tools and shafting.

Further in accordance with the present invention, the cabinet may be divided into separate convenient sections for the motors and dust collecting system, respectively, and the hood shrouding the tools is partitioned to provide separate compartments for the various groups of tools. Preferably, the means dividing the cabinet into sections comprises upright frame members extending substantially the full height of the apparatus, the upper portions of these frame members forming parts of the partition means dividing the hood. These upright frame members preferably afford support for shaft bearings which may be housed on either side of each frame member. Thus arranged, all of the tools are partially shrouded to prevent accidental contact therewith while running and are protected from dust and dirt. All bearings are completely housed and the belting or other transmission means for delivering power of the motor equipment to the shafting is housed within the cabinet and the hood. All exposed surfaces of the structure, being continuous, may be easily maintained in a clean condition and afford display areas which may be finished in keeping with other appointments of the repair shop. The dust collecting system, also, is housed within the metal casing, thereby minimizing the fire hazard.

These and other features of the invention, including certain details of construction and combinations of parts, will be set forth in connection with an illustrative machine and will be pointed out in the appended claims.

Referring now to the accompanying drawings, Fig. 1 is a perspective view of the improved apparatus;

Fig. 2 is a perspective view showing the interior of the improved apparatus;

Fig. 3 is a perspective view showing the frame construction;

Fig. 4 is an end view of one of the upright frame members of the machine;

Fig. 5 is a sectional view taken on the line V—V of Fig. 4;

Fig. 6 is a sectional view taken on the line VI—VI of Fig. 3; and

Fig. 7 is a fragmentary cross sectional view of the improved apparatus.

The improved apparatus herein illustrated is provided with a plurality of brushing and polishing tools 10 (Fig. 1), scouring and buffing tools 12, a shank buffering tool 14 and edge trimming tools 16, all of which are well-known in the art and are common equipment in shoe repairing machinery. All of these tools are housed in a

re-entrant space formed in the upper portion of a cabinet-like housing structure or casing to provide an open-front hood for the tools. This casing is shown generally in Fig. 1, and comprises a front wall 18, a rear wall 20, and end closures 22 and 24. Closing the casing beneath the various tools is a deck 26, conveniently of bench height. The front wall 18 extends upwardly to the level of the deck 26, the junction of the front wall with the deck being closed. The rear wall 20 extends upwardly above the level of the deck 26, curving forwardly at its upper portion and extending forwardly over the deck 26 and the various tools to provide the above-mentioned hood beneath which the tools are housed. Suitable illumination is provided by lamps 28 above the tools and within the hood. The deck 26 may extend rearwardly all the way to the rear wall 20 or, as in the illustrated construction (see Figs. 1 and 2 and particularly Fig. 7), the rear edge of the deck 26 may be continuous with the lower edge of an upwardly extending back wall 30 which is spaced forwardly of the rear wall 20 and which has its upper edge against the inner surface of the upper portion of the rear wall 20. The deck 26 and the back wall 30 thus separate the hood above referred to from what may generally be termed the interior portion of the casing, and define the re-entrant space in which the tools are housed.

A horizontal shaft 32 carries the brushing and polishing tools 10, and a shaft 34 coaxial therewith carries the scouring and buffing tools 12. The axis of these shafts is far enough forward to bring the tools conveniently within the reach of the operator, this axis, in the illustrated construction, lying substantially in the plane of the front wall 18. As shown in Fig. 1, the casing may be divided longitudinally into a plurality of sections. In the interior portion of one of these sections is housed a motor 36 (Fig. 2) which drives the shaft 32 through a belt 38. In another section is housed a motor 40 which drives the shaft 34 and the edge trimming tools 16 through connections later to be described. Starting switches 31 and 41 are provided for the motors 36 and 40, respectively.

Associated with the scouring and buffing tools 12 and with the shank buffering tool 14 are individual dust hoods 44. These hoods communicate with a manifold 45 (Fig. 7) which extends longitudinally of the machine and conducts dust-laden air from the hoods to a dust separating apparatus 48 housed in the interior of the middle section of the casing. This dust separating apparatus may be of any well-known construction, preferably having a filter. A blower 50 (the upper portion of the circular blower housing is visible in Fig. 2) is provided for creating the necessary suction at the dust hoods and for forcing the air from the dust hoods through the separating apparatus. The blower 50 discharges clean air into the interior of the cabinet-like structure.

The driving arrangement for the scouring, buffering and edge trimming tools, as shown in Fig. 2, comprises a countershaft 52 journaled in bearings 54 (one of which is shown in Fig. 2) mounted within the interior of the casing and driven from the motor 40 by a belt 53. The drive from the countershaft 52 to the shaft 34 is transmitted by a belt 56 running over pulleys on the respective shafts, the lower pulley being loose on the shaft 52 and capable of being coupled thereto at will by a clutch mechanism hav-

ing a control handle 58. The shank buffering tool 14 is driven from the shaft 34 through a belt 60 passing over suitable pulleys. The edge trimming tools 16 are driven from the countershaft 52 through a belt 62 running over suitable pulleys, including a loose pulley on the countershaft which may be coupled thereto at will by a clutch mechanism having a control handle 64. The blower 50 is driven through a belt 65 from the countershaft 52.

Several members which appear in Fig. 2 and which have not yet been mentioned are an edge setting tool 66 on the end of the shaft 32 which extends outside of the casing, a pair of ink pots 68, a device 70 for applying abrasive covers to the removable padded shank buffering tool 14, a suction opening 72 in the back wall 30 for receiving dust-laden air from the edge trimming tools 16, and a section opening 74 in the shaft 24 for receiving chips falling from the edge trimming tools 16. These suction openings 72 and 74 lead into the above-mentioned manifold. There is provided also a grinder 75 for sharpening the edge trimming tools, and a work rest 73 for use in connection with the grinder 75. The shank buffering tool 14 has a housing 77 supported by a bracket 79. The edge trimming tools 16 are supported by a bracket 81. A switch 83 controls the lighting of the lamps 28.

The construction of the casing will now be described. As shown in Fig. 3, the supporting structure of the casing comprises a plurality of upright frame members 76, 78, 80, 82 and 84. The members 76 and 84 are adjacent to the ends of the casing; the members 78 and 80 are spaced closely to each other between the left and the middle sections of the casing, while the member 82 is between the middle and the right-hand sections. The members 78 and 80, as will later appear, constitute the end frame members of separable units which make up the illustrated casing. All of the above-mentioned frame members are similar to each other, each being built up of four separate pieces which for convenience will be identified by the same reference numerals for all of the upright frame members. Two of these four pieces consist of a pair of sheet metal plates 86 and 88 (Figs. 5 and 6) spot welded together at localities indicated by the reference numeral 90. For the purpose of lightening the construction, openings 92 (Fig. 4) are provided in the plates 86 and 88 and greater stiffness is obtained by spacing the inner portions of the plates 86 and 88 apart at the localities indicated by the reference character 94, the plates being welded together at their marginal portions surrounding the openings 92 and adjacent to their exterior marginal portions. An opening 95 also is provided to accommodate the suction manifold 45. A portion of the space 94 serves conveniently to house wiring 97 (Fig. 4) leading to the lamps 28. The forward marginal portions of the plates 86 and 88 are flanged outwardly in opposite directions as indicated by the reference numerals 96 and 98 (best shown in Fig. 6) and spot welded to these flanges is a third piece in the form of a flat upright reinforcing plate 100. The flanges 96 and 98 and the plate 100 extend upwardly from the floor to about the level of the shelf 26. The rear marginal portions of the plates 86 and 88 are flanged outwardly (Fig. 5) in opposite directions as indicated by the reference numerals 102 and 104 and spot welded to these flanges is a fourth piece in the form of a reinforcing plate 106. The

flanges 102 and 104 and the plate 106 rise upright from the floor to a point some distance below the level of the deck 26 and then gradually curve forwardly, the curvature increasing above the level of the deck 26. The flanges 102 and 104 and the plate 106 continue forwardly around the curved top of the plates 86 and 88 and terminate a short distance below the level of said top and a considerable distance above the level of the deck 26. The forward ends of the flanges 102 and 104 and the plate 106 are a little forward of the plane of the plate 100; the intervening unflanged edges of the plates 86 and 88 are together and extend forwardly beyond the plate 100 in a convex curve which is a continuation of the curvature of the plate 106 and which terminates at the upper end of the plate 100. In this intervening portion is formed a notch 108 to receive one of the shafts 32 or 34. A bearing 109 for the shaft is secured to the face of one of the plates 86 or 88 at the notch 108. The lower end portions of the plates 100 and 106 are bent horizontally to provide feet 110 which rest upon the floor and carry the weight of the structure. Welded to the front feet are upright lateral flanges 111 (Figs. 2 and 3) extending from the upright portions of the plates 100 and 106.

The bearings 109, as has already been pointed out, are carried by the upright frame members. In addition, the frame member 76 carries brackets which support the ink pots 68, and the frame member 82 carries the bracket 79 for supporting the shank buffering tool 14. The frame member 82 also carries a bracket 55 for supporting the countershaft bearing 54. The frame member 84 carries the bracket 81 which supports the edge trimming tools.

Connecting the frame members 76 and 78 adjacent to their forward feet is an angle iron 112 (Figs. 2 and 3). An angle iron 114 connects the frame members 80 and 82 and an angle iron 116 connects the frame members 82 and 84. Also connecting the lower portions of the frame members 76 and 78 is a shelf 118 which is stiffened by corrugations and by depending lateral flanges. The motor 36 is secured upon the shelf 118. A pair of brackets 120 likewise connects the frame members 80 and 82 and supports the dust separator 48, and a shelf 122 similar to the shelf 118 connects the frame members 82 and 84 and supports the motor 40. Connecting the frame members 76 and 78 at the front edge of the deck 26 is a curved metal plate 124. A member 126 similar to the plate 124 connects the frame members 80 and 82 and a similar member 128 connects the frame members 82 and 84.

A sheet metal plate 130 (Figs. 3 and 5) extending upwardly from close to the floor has its opposite lateral margins secured to the rear reinforcing plates 106 of the upright frame members 76 and 78 respectively, following the curvature of the plates 106 and terminating at the upper ends of the plates 106. A similar plate 132 connects the frame members 80 and 82, and a plate 134, also similar to the plate 130, connects the frame members 82 and 84. The plates 130, 132 and 134 contribute materially to the longitudinal stiffness of the entire housing. Together they comprise the principal portion of the rear wall 20. Louvers 136 (Fig. 3) provide for the quiet passage into the room of the clean air which has been released into the interior of the casing from the dust collector.

It has already been mentioned that the casing is made up of two units which are longitudinally

separable between the frame members 76 and 78. These units are connected by an upper pair of tie bolts 138 and 140 (Figs. 3 and 4) and a lower pair of tie bolts 142 and 144 (Figs. 4 and 5).

- 5 The lower tie bolts may conveniently be employed also to secure the adjacent ends of the shelf 118 and brackets 120. The break between the two units is covered in the rear by a plate 146 (Fig. 5) and in front by a plate 148 (see also Fig. 3).
 10 The opposite lateral margins of the plate 146 overlap the plates 130 and 132 and are conveniently secured in position by a row of screws (threaded into lugs 150) which secure the plate 130 to one of the plates 106 and by a row of screws (threaded into lugs 152) which secure the plate 132 to another of the plates 106. Each of these screws secures also a metal clip 154, each row of clips holding yieldingly in position a resilient metal cover strip 156. The plate 148 similarly covers the two adjoining front reinforcing plates 100 of the frame members 76 and 78, having its lateral margins secured to the reinforcing plates by rows of screws 158. Each row of screws 158 is concealed by a cover strip 160.

- 25 The left-hand end of the casing is closed by the end closure 24, which is a wall of sheet metal similar in outline to the upright frame members and adjacent to the frame member 76. The end closure 24 has a flanged margin 164 (Fig. 6) whereby it is secured to the reinforcing plates 100 and 106 of the frame member 76. An outer plate 166 (Fig. 3) covers the rear reinforcing plate 106, the lateral margins of the plate 166 overlapping the flange 164 and the plate 130 respectively, and being secured through the flange 164 and the plate 130 to the rear reinforcing plate 106 by rows of screws concealed by cover strips. An outer plate 168 (Fig. 6) similar to the plate 148 covers the front reinforcing plate 100, the left-hand lateral margin of the plate 168 overlapping the flange 164. A row of screws 170 concealed by a cover strip 172 secures the flange 164 and the lateral margin of the plate 100. The right-hand lateral margin of the plate 168 overlaps a jamb strip of sheet metal 174 the purpose of which will presently be explained. A row of screws 176 concealed by a cover strip 178 secure the jamb strip 174 and the lateral margin of the plate 168 to the reinforcing plate 100.

- 50 The front cover plate 148, already described, does not lie against the reinforcing plate 100 of the frame member 78, but overlaps a pair of oppositely extending jamb strips 180 and 182 (Figs. 2, 3 and 5). The front and rear reinforcing plates of the frame member 82 are similarly covered by plates 184 and 186 respectively, a pair of oppositely disposed jamb strips being provided at the lateral margins of the front reinforcing plate. The right-hand end of the casing is closed by the end closure 22, which is similar to the end closure 24 and is secured in a similar manner, in connection with front and rear cover plates 190 and 192 respectively, to the frame member 84. The large openings between the four upright front cover plates already described are normally closed by panels 194, 196 and 198 (Fig. 1) which are completely removable. These panels carry upon their inner faces clips 195 which hook over the upright flanges of the angle irons 112, 114 and 116, respectively, and also latches 197 in the form of rubber rolls which yieldably engage the lower edges of the longitudinal members 124, 126 and 128, respectively. The several jamb strips above mentioned serve as abutments 75 for the lateral edges of the panels. These panels,

together with the upright front plates, constitute the front wall 18.

It has already been mentioned that a deck 26 of convenient bench height is provided beneath the tools. This deck is, of course, interrupted to accommodate the several intermediate upright frame members. The front edges of the several units of the deck are secured to the upper or rear edges of the curved longitudinal plates 124, 126 and 128. The back wall 30 (Fig. 7), which in the illustrated construction is continuous with the deck 26, extends upwardly in back of the various tools and then forwardly in contact with the under surfaces of the upper portions of the rear wall plates 130, 132 and 134. The upper portion of the back wall 30 carries housings 200 for the lamps 28. End walls 202 of sheet metal extending upwardly from the deck 26 and forwardly from the back wall 30 separate the spaces reserved for the various tools from the spaces occupied by the upright frame members. The upper portions of the end walls 202 are secured for support to the flanges 102 or 104 of the upright frame members. These end walls 202 are notched to accommodate the shafts 32 and 34. The end wall 202 adjacent to the left-hand frame member 76 serves as a closure member for the space occupied by the ink pots 68, the upper portion of the belt 38, and the pulley on the shaft 32. The end walls 202 adjacent to the upright frame member 82 serve as closure members for the space occupied by the belts 60 and 56 and various pulleys associated therewith. The end walls 202 adjacent to the right-hand frame member 84 serve as a closure member for the belt 62, the cutter grinder, and various other features connected with the edge trimmers. One of the end walls 202, as shown in Fig. 2, carries the lighting switch 83.

For completing the closure of the above-mentioned spaces between the adjacent pairs of end walls 202 and between the end closures 22 and 24 and the end walls 202 respectively adjacent thereto, there are provided doors 204 (Fig. 1) dependingly hinged to the forward or upper edges of the various rear reinforcing plates 106. The doors 204 may be opened by swinging them upwardly to a stop position beyond dead center. When closed they are held by yieldable latches. Each door is substantially equal in width to the rear cover plate 166 and the forward cover plate 168 between which it extends. The two end doors 204 are each provided with an upright rearwardly extending flange 206 which closely overlaps the adjacent end wall 202 when the door is closed. The two intermediate doors 204 are each provided with a pair of similar flanges 206 which likewise overlap the adjacent end walls 202 when the doors are closed. The flanges 206 are notched to accommodate the shafting.

It will be noted that the two casing units which are connected by the tie bolts 138, 140, 142 and 144 are each self-contained. Each unit has its own shaft, its own motor, and its own set of tools, and operates independently of the other unit. Inasmuch as the groups of tools in the respective units are for different types of work, it is sometimes convenient to supply the units separately. When an individual unit is to be installed, the end adjacent to the partition 78 or 80, as the case may be, is closed by the appropriate member 24 or 22. The units may be provided with tools other than those disclosed herein, and may be connected end to end like

a sectional bookcase in any arrangement suitable to the sequence of operations to be performed. The apparatus can be manufactured, handled and shipped in individual units more conveniently and economically than if it were made in a single large piece, and the connections between the individual units are readily made upon installation.

Each of the units above mentioned comprises upright frame members and an exterior casing wall. For example, the left-hand unit has the two upright frame members 76 and 78, and an exterior casing wall comprising the members 24, 166, 168, 130, 194, 26, 30. When this unit is intended to be shipped for connection to the right-hand unit, the upright frame member 76 will be within the exterior wall, but the upright frame member 78 will be exposed. Likewise, the upright frame member 80 of the right-hand unit will be exposed. After the two units have been connected together these exposed frame members will be covered by the members 146, 148 and the door 204 which together constitute a continuation of the exterior walls of the two units.

It is evident that the construction which has been described presents many advantages. The tools 12, 14 and 16, while conveniently accessible to the operator, are nevertheless so housed by the hood structure comprising the rear plates 130, 132 and 134, the back walls 30, the deck 26 and the end walls 202 as to prevent any dust, dirt or chips which might not be caught by the draft hoods 44 from getting into the room. The various bearings, the pulleys, belting, motors, etc., are completely housed, thereby preventing any oil from the bearings from being spattered about and also protecting persons from contact with the moving parts. The dust separator 48 likewise is completely housed within the body of the apparatus, reducing the fire hazard. The upright frame members 76, 78, 80, 82 and 84 are also completely housed. Such housing of the tools and accessories and of a considerable part of the frame not only makes for compactness but contributes to the pleasing appearance of the apparatus. The rear plates 130, 132 and 134 serve not only as housing members but are important parts of the frame structure, contributing materially to the strength and rigidity of the apparatus. This form of construction is easy and cheap from a manufacturing standpoint and requires a minimum of material to obtain the desired strength, combining the advantages of economy of production and lightness of weight. Ready access to the motors, dust collector and interior mechanism is provided by the removable panels 194, 196 and 198, and by the doors 204.

Having thus described my invention, what I claim as new and desire to secure by Letters Patent of the United States is:

1. A machine for operating on shoes comprising a cabinet-like casing having a re-entrant space formed in the upper portion thereof to provide an open-front hood, a shaft extending lengthwise of the casing, rotary tools mounted on the shaft and shrouded by the hood, a motor contained in the lower portion of the casing and arranged to drive the shaft, and dust collecting apparatus also contained in the lower portion of the casing, one of the walls of the casing being provided with a panel removable to give access to the interior of the casing.

2. A machine for operating on shoes comprising a cabinet-like casing having a re-entrant

space formed in the upper portion thereof to provide an open-front hood, a shaft extending lengthwise of the casing, rotary tools mounted on the shaft and shrouded by the hood, the lower portion of the casing being divided into sections, a motor contained in one of said sections and arranged to drive the shaft, and a dust collecting apparatus contained in another of said sections, one of the walls of the casing comprising separate removable panels permitting individual access to the several sections.

3. A shoe repair apparatus comprising a cabinet-like structure of bench height, having a rear wall, end walls and a front wall, shafting supported over said structure, a plurality of finishing tools mounted on said shafting, a motor and a dust collector housed within the structure, an open-front hood over said structure and extending forwardly over said tools, and connections housed within the structure for transmitting the drive of said motor to said shaft.

4. A shoe repair apparatus according to claim 3, having upright frame members which divide the cabinet-like structure into sections, said dust collector and said motor being housed in separate sections, and bearings for said shafting carried by said frame members.

5. A shoe repair apparatus having a deck extending lengthwise thereof, a shaft above and extending lengthwise of the deck and carrying a plurality of finishing tools, a motor carried beneath the deck and arranged to drive the shaft, and a housing structure of which the deck forms the upper wall enclosing the motor and such other portions of the mechanism as are located beneath the deck, the rear wall of said housing extending upwardly above the deck and then forwardly as a hood above the shaft and the tools carried thereby.

6. A shoe repair apparatus comprising a shaft carrying a plurality of finishing tools, a motor carried beneath the shaft and arranged to drive the shaft, a dust collector also carried beneath the shaft and arranged to receive and store dust and chips resulting from the operation of the tools, and a housing structure closed beneath the shaft and enclosing the motor, the dust collector and such other portions of the mechanism as are located beneath the shaft, the rear wall of said housing extending upwardly above the closed portion of the housing structure and then forwardly as a hood above the shaft and the tools carried thereby.

7. A shoe repair apparatus comprising a shaft carrying a plurality of finishing tools, a housing structure closed beneath the shaft, the rear wall of said housing structure extending upwardly above the closed portion of the housing structure and then forwardly as a hood above the shaft and the tools carried thereby, a partition dividing the hood and separating the tools into convenient groups, and a bearing for said shaft carried by said partition.

8. A shoe repair apparatus comprising a shaft carrying a plurality of finishing tools, a housing structure closed beneath the shaft, the rear wall of said housing structure extending upwardly above the closed portion of the housing structure and then forwardly as a hood above the shaft and the tools carried thereby, a partition dividing the hood into separate compartments and separating the tools into convenient groups, a bearing for said shaft carried by said partition, and a lamp carried under the front

edge of the hood in each compartment whereby each group of tools may be illuminated.

9. A shoe repair apparatus comprising a shaft carrying a plurality of finishing tools, a housing structure closed beneath the shaft, the rear wall of said housing structure extending upwardly above the closed portion of the housing structure and then forwardly as a hood above the shaft and the tools carried thereby, a partition dividing the hood and separating the tools into convenient groups, a bearing for said shaft carried by said partition, said partition comprising upper end portions of vertical supporting frame members, the lower portions of which divide the closed portion of the housing structure into separate convenient sections, a motor in one of said sections for driving the shaft, dust collecting apparatus in another of said sections, and a transmission enclosed within the housing structure and hood and connecting the shaft with said motor.

10. A machine for operating upon shoes comprising a pair of spaced parallel upright frame members having the lower portions of their forward edges rising vertically from the floor and the upper portions of their forward edges extending forwardly beyond the vertical lower portions, said frame members having also rear edges the upper portions of which curve forwardly, a connecting structure between said upright members, a horizontal tool shaft having its axis substantially in the plane of the vertical portions of the forward edges of the upright frame members, and bearings on the upright frame members for said shaft.

11. A machine for operating on shoes comprising a plurality of upright frame members, connecting frame members between said upright members, a shaft, tools on said shaft, bearings for said shaft carried by said upright frame members, and a housing surrounding said upright frame members and said bearings, said housing being recessed to provide a re-entrant space in the form of an open-front hood for said tools between the upper portions of said upright frame members.

12. A machine for operating on shoes comprising a pair of upright end frame members, an upright intermediate frame member between said end frame members, connecting frame members between said upright frame members, a shaft, tools on said shaft between each of said upright end frame members and said upright intermediate frame member, bearings for said shaft carried by said upright frame members, and a housing surrounding said upright frame members and said bearings, said housing being recessed to provide a re-entrant space in the form of an open-front hood for said tools between each of said upright end frame members and said upright intermediate frame member.

13. A machine for operating on shoes comprising a pair of upright end frame members, a pair of upright intermediate frame members adjacent to each other between said end frame members, a connecting frame member between each end upright member and the intermediate upright member nearer to that end, a shaft between one of said upright end members and the upright intermediate member nearer to that end, a second shaft between the other upright end member and the intermediate member nearer to that end, tools on each of said shafts, an exterior casing wall around one upright end member and

extending to the nearer upright intermediate member, an exterior casing wall around the other upright end member and extending to the nearer upright intermediate member, each of said casing walls being recessed to provide a re-entrant space in the form of an open-front hood for said tools, each upright end member together with its casing wall, intermediate upright member, connecting frame member, shaft and tools as so far recited constituting a unit, a tie connection between said intermediate frame members for uniting the two units into a single structure, and a covering for said intermediate upright frame members, said covering constituting a continuation of said casing walls to complete the closure of said intermediate upright frame members.

14. A machine for operating on shoes comprising a casing having an exterior enclosing wall and a plurality of upright frame members spaced longitudinally of the casing within the exterior enclosing wall, a shaft, tools on said shaft car-

ried by said upright frame members, and a motor and driving connections therefor within the exterior enclosing wall, said exterior enclosing wall being recessed to provide a re-entrant space in the form of an open-front hood for said tools between the upper portions of said upright frame members.

15. A shoe repair apparatus having a plurality of tools, a cabinet-like casing supporting said tools, a motor, driving connections from said motor to said tools, means for drawing dust-laden air from the vicinity of the tools, and means for separating the dust from said dust-laden air and for returning clean air to the atmosphere, said casing having an upper hood-like structure extending over the tools, and having a partition arranged to separate the tools into convenient groups, and having also lower compartments for said motor and said dust-separating means respectively.
